[57] CLAIM

The ornamental design for a sitting device for a golf putter, as shown and described.

DESCRIPTION

FIG. 1 is a front elevational view of a sitting device for a golf putter showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a front elevational view of a second embodiment of the sitting device for a golf putter as disclosed in FIG. 1;

FIG. 8 is a rear elevational view of FIG. 7;

FIG. 9 is a left side elevational view of FIG. 7;

FIG. 10 is a right side elevational view of FIG. 7;

FIG. 11 is a top plan view of FIG. 7; and,

FIG. 12 is a bottom plan view of FIG. 7.

The broken line showing of a golf club head is for illustrative purposes only and forms no part of the claimed design.
